MARKER LIGHT

Willis A. Pennow, Cleveland, Ohio, assignor to Westinghouse Electric & Manufacturing Company, East Pittsburgh, Pa., a corporation of Pennsylvania

Application June 27, 1941, Serial No. 400,012

10 Claims.

(Cl. 240—1.2)

My invention relates, generally, to marker lights and, more particularly, to incandescent marker lights of the substantially flush-mounting type adapted primarily to outline runway and taxi areas of airports, for use as range lights and traffic lights and as contact lights for airports. The present invention is an improvement upon the marker light disclosed by my United States Letters Patent No. 2,184,004, dated December 19, 1939.

The object of my invention, generally stated, is to provide an improved marker light for airports and the like which shall be of simple and rugged construction, economical to manufacture and install, and which may be readily adapted for use in a variety of ways in connection with airport lighting.

A more specific object of my invention is to provide a marker light structure wherein the main or outer lens is mounted on top of the main cover or top ring of the housing in an exposed position outside the vertical rib members which support the cover or relamping plate.

A further object of my invention is to provide in a marker light for utilizing a main or outer lens which is essentially self-cleaning to a considerable degree and which is so constructed that it may be mounted in an exposed position where it is subject to blows and impacts from the wheels, tailskids, etc. of aircraft and the like, without danger of breakage.

Another object of my invention is to provide a marker light of the character described which may be readily opened above ground level for relamping and cleaning of the various parts thereof.

A further object of my invention is to provide a marker light wherein the relamping cover plate is supported by ribs or fins on the main cover of the housing so positioned as not to collect sand and dirt and not to obstruct the outside surface of the outer lens.

These and other important objects of my invention will become more apparent from the following detailed description when read in conjunction with the drawing wherein:

Figure 1 is an elevational view, partly in section along line II—II of Fig. 2, of a marker light embodying the principal features of my invention, and

Fig. 2 is a top view of the marker light of Fig. 1 with a portion of the cover plate broken away to show the relative positions of the lenses and also their positions with respect to the ribs on the top cover of the housing.

Referring to the drawing the embodiment of my invention disclosed is intended for use in the same general way as that disclosed by my Patent No. 2,184,004 and also produces the same general kind of light distribution. In other words, it functions to concentrate the light in a vertically narrow beam from 2 to 10 degrees above the horizontal. This distribution may be symmetric or asymmetric, depending upon the type of outer lens used and the light produced may be clear or colored as desired depending upon the way in which the marker light is used.

The numeral 10 designates the housing or body portion which is preferably constructed of cast iron, the particular housing shown being that of a unit for multiple wiring service. It is provided adjacent the bottom with side openings 11 threaded to receive the wiring conduits 12, as shown.

20 A suitable socket 13 for supporting an incandescent lamp 14 in a vertical position is mounted within the housing as shown in Fig. 1.

The housing 10 is provided with a main cover 15, preferably constructed of a steel alloy, detachably secured to the upper rim of the housing by a plurality of spaced stud bolts 16. The upper rim of the housing is preferably shaped as shown in Fig. 1, to provide an annular channel 17 defined by the annular inner and outer flange portions 18 and 19. The main cover 15 is provided with an annular channel 21 into which is placed a composition rubber gasket 22 which is subjected to heavy compression by the narrow surface area of the inner flange portion 18 to provide a moisture-proof seal between the main cover and the housing so that this joint may be placed at or below ground level.

40 The main cover 15 is relatively flat across the top and is provided with a central opening 23 through which the lamp 14 extends.

In order to provide the desired light distribution, a suitable inner Fresnel or prismatic lens 24 is positioned about the lamp 14 and is preferably supported by the flanged inner edge 25 of the main cover although it may be supported in such position in any other suitable manner. While I have shown a generally ring-shaped or cylindrical lens with prisms on the outside thereof for this purpose, it is to be understood that 50 any other suitable type or shape of lens may be used so long that it functions to produce the desired light distribution.

In this embodiment of the invention, an outer lens 26 is used and is also preferably supported by the main cover 15, the bottom edge thereof

being disposed in an annular channel 27 in the top surface of the cover, as shown. This lens is constructed of clear heat and impact resisting glass with a smooth inwardly sloping outside surface so as to be essentially self cleaning and so that it will not accumulate sand and dirt which may be blown against it.

The particular outer lens shown is of truncated cone shape having substantially parallel upper and lower edge portions. When this lens is used as a protective lens, it is of a plain type, i. e., without prisms, but when it is to be used both as a protective lens and a light directing lens, it is preferably provided with internal vertical prisms 31, as shown, these prisms being used to control the horizontal light distribution in any desired manner such as by concentrating the light in one or more zones.

In order to provide ready access to the interior of the unit for relamping and the like, it is provided with a removable cover plate 32 supported above and in covering relation to the inner and outer lenses. In this instance, the cover plate is supported by means of a plurality of vertical rib or fin members 33 preferably cast integral with the main cover 15. As shown, these ribs are disposed in spaced radial relation about the central opening in the main cover between the inner and outer lenses. In such position, these ribs function to effectively support the cover plate 32 and are so positioned that they do not collect sand and dirt.

The cover plate 32 may be detachably secured to the upper ends of the ribs 33 by screws 34. The cover plate is provided with a flanged outer edge 35 extending outwardly over the upper edge of the outer lens. An L-shaped gasket 36 of suitable material is interposed between the upper edge of the outer lens and flange 35 and a similarly shaped gasket 37 is positioned in the annular channel 27 in the main cover between the surface of the cover and the lower edge of the lens.

The height of the ribs 33 is such that when the cover plate 32 is drawn down tightly against the upper ends thereof, the gaskets 36 and 37 are compressed to provide tightly sealed joints without applying an excessive loading or pressure upon the outer lens. The gaskets 36 and 37 are L-shaped to provide a cushion for lateral thrusts to which the outer lens may be subjected.

The inner lens 24 is preferably mounted loosely within the space defined by the inner edges of the ribs 33 with its upper edge out of engagement with the bottom surface of the cover plate 32. If desired, the cover plate may be provided with an annular flange portion 38 which not only serves to relieve the attaching screws 34 from side thrust but also to retain the inner lens in the desired position.

If desired, the unit may be provided with a reflector 39 mounted below the lamp bulb and preferably supported from the main cover by means of screws 40. The reflector may be constructed of aluminum or any other suitable material and is so shaped as to have a wide angle of acceptance so that it functions to redirect practically all of the light below the horizontal back through the light center to the optical or lens system.

The unit described may be used at airports in a number of ways such for example, as flush boundary lights, marker circles, contact lights, flush range lights, taxi lights and flush traffic

lights. Any color of light desired may be produced by utilizing lenses of the desired color.

Where it is desired to use an outer lens with internal prisms to produce asymmetric distribution, a lens position indicator 41 may be applied to the unit. This indicator may comprise a movable pointer plate attached to the top of the main cover by screws 42, as shown in Fig. 2, the pointer 43 of the plate being aligned with an arrow 44, or other mark, on the outside of the outer lens when this lens is properly positioned to direct the beam or beams in the desired direction. This makes it possible to remove the outer lens for servicing and to replace it in the proper position without observing or checking the position or direction of the beams.

In view of the foregoing it will be apparent that my invention provides a marker light structure which is of simple and economical construction and which has important advantages over the prior art structures. It is so constructed that it is not only rugged and moistureproof but also readily opened above ground level for servicing. Furthermore, the contour of its exposed upper surface is such that it remains effective under all operating conditions for the reason that it does not collect sand and dirt and is essentially self cleaning.

While I have shown and described a particular embodiment of my invention, it will be obvious to those skilled in the art that changes and modifications may be made therein without departing from the principles set forth and defined by the appended claims.

I claim as my invention:

1. A runway marker light comprising, a metal housing adapted to be embedded in the surface of a runway or the like and having a top cover portion provided with a central opening, said top cover portion having a plurality of rigid upstanding support members thereon, a generally ring-shaped lens mounted upon the top cover portion in surrounding relation to the support members, and cover plate means for said lens detachably supported by said support members in a rigid manner in predetermined spaced relation to the top cover portion of the housing.

2. A marker light comprising, a bowl-shaped metal housing, a metal cover member for the housing having a central opening therein, said cover member having a plurality of spaced upwardly extending rigid rib members on its upper surface between its inner and outer edges, a first generally ring-shaped lens mounted within the central opening in said cover member inside the rib members, a second generally ring-shaped lens supported by the cover member outside the rib members, and cover plate means detachably secured to the upper ends of the rib members over said first and second lenses, said rib members functioning to rigidly support the cover plate means in predetermined spaced relation with the metal cover member of the housing.

3. A runway marker light comprising, a metal housing provided with a top cover member having a central opening therein and a plurality of rigid upstanding rib members thereon, a first generally ring-shaped lens mounted to extend above the top cover member inside the rib members and in generally concentric relation with the central opening, a second generally ring-shaped lens mounted upon the top cover member on the outside of said rib members, gasket means interposed therebetween, cover plate means supported by the rib members over the

lenses, means securing the cover plate means to the upper ends of the rib members, said cover plate means extending outwardly over the top edge of the second lens, gasket means interposed therebetween, and means for securing the cover plate means to the rib members, said rib members functioning to rigidly support the cover plate means in predetermined spaced relation to the top cover member of the housing.

4. A marker light comprising, a metal housing having upper and lower sections joined together by a fluid-tight joint, said lower section adapted to be set into the surface of a runway or the like, said upper section being provided with a central opening and having a plurality of rigid upstanding support members thereon surrounding said opening, a generally ring-shaped lens mounted on the upper section of the housing in surrounding relation to the support members, cover plate means mounted on the support members and having an outwardly extending flange portion extending over the upper edge of the lens, said support members being of such height as to rigidly support the cover plate means in predetermined spaced relation to the upper section of the housing, gaskets interposed within the joints between the upper and lower edges of the lens and the top surface of the upper section of the housing and lower surface of the flange portion of the cover, and means for detachably securing the cover plate means to the support members and compressing said gaskets, thereby to provide a watertight assembly and a rigid support for the cover plate means a predetermined distance above the upper section of the housing.

5. A marker light for use in marking runways of airports and the like comprising, a generally bowl-shaped metal housing having a cover portion with a central opening and a plurality of rigid spaced upstanding support members thereon about the central opening, a generally frusto-conical lens positioned upon the cover about the support members, and cover plate means for said lens detachably secured to the support members.

6. A marker light for use in marking runways of airports and the like comprising, a generally bowl-shaped metal housing having a cover portion with a central opening and a plurality of rigid spaced upstanding rib members thereon about the central opening, said cover portion having an annular seat thereon adjacent its outer edge, a gasket member disposed on said seat, a generally frusto-conical lens mounted on said gasket, cover plate means supported by said rib members over the lens, a gasket member interposed between the upper edge of the lens and rim of the cover plate means, and means detachably securing the cover plate means to the upper ends of the rib members, said means functioning to draw the cover plate means into engagement with said rib members and compress the gasket members to form tight joints.

7. A marker light for use in marking runways of airports and the like comprising, a bowl-shaped metal housing having a cover portion with a central opening therein, a generally ring-shaped inner lens mounted adjacent the central

opening, a generally frusto-conical shaped outer lens of larger diameter supported by the cover about the inner lens, cover plate means detachably supported by the cover over said lenses, and 5 gaskets positioned in the joints between the upper and lower edges of the outer lens and the cover plate means and cover portion, respectively, to provide water-tight joints therebetween.

8. A marker light for use in marking runways 10 of airports and the like comprising, a generally bowl-shaped metal housing adapted to be set into the runway or other surface, a metal cover for said housing attached thereto by a fluid-tight joint, said metal cover having a central opening 15 therein and an annular groove adjacent the outer rim thereof, a socket mounted within the housing for supporting a lamp within the central opening, a generally ring-shaped lens mounted about the lamp in the central opening, a frusto-conical lens of larger diameter having a smooth outer surface mounted in said annular groove, cover plate means for said lenses rigidly supported thereabove from the metal cover of the housing, and gaskets positioned in the joints 20 between the upper and lower edges of the frusto-conical lens and the cover plate means and housing cover, respectively, to make said joints watertight.

9. A runway marker light for use in marking 30 runways of airports and the like comprising, a generally bowl-shaped housing adapted to be set into the ground and having a cover with a relatively large central opening therein, said cover having an annular seat on a portion of its upper 35 surface adjacent the outer edge thereof, an annular lens positioned on said seat, cover plate means of opaque material positioned over the lens to close the upper end thereof, and rigid support members interposed between the cover 40 of the housing and the cover plate means inside the annular lens for rigidly supporting said cover plate means in predetermined spaced relation to the cover of the housing.

10. A runway marker light comprising, a housing 45 having a cover with a central opening, a lamp socket mounted within the housing to support a lamp within said central opening, said cover having an annular seat on its upper surface adjacent the outer edge thereof, an annular lens positioned on said annular seat, gasket means positioned between the surface of the annular seat and the bottom edge of the lens, cover means positioned over said lens to close the top opening thereof, gasket means positioned between the 50 cover means and the upper edge of the lens, and means including rigid support members interposed between the cover of the housing and the cover means on the inside of the lens for rigidly supporting the cover means and clamping said 55 cover means, lens and housing cover tightly together, thereby to subject said gasket means to sufficient pressure to provide a watertight assembly and maintain the cover means and the cover of the housing in predetermined spaced relation.

WILLIS A. PENNOW.
